CALL RECORDING APPARATUS FOR
TELEPHONES

Jacob E. Laskin, Shaker Heights, Ohio

Application August 3, 1933, Serial No. 683,435

25 Claims. (Cl. 179—11)

This invention relates to call-recording mechanism for use with automatic telephones, and the primary object of the same is to provide mechanism of this type which is compact and 5 may be built into the telephone unit or sold as a separate attachment therefor and which records only the chargeable calls, is reliable and efficient in operation and at the same time is of such simplified construction as to bring its cost within 10 the range demanded by the nature of its service.

The present improved counting mechanism is primarily adapted for use with phone systems of the reverse current type, and includes in its assembly a polarized relay which places the actuating means for the counter in condition to be operated by the receiver hook. It is desirable that this relay be cut out of the main phone circuit during talking as well as during the dialing operation to prevent transmission losses. Accordingly, another object of the invention is to provide counting mechanism for automatic telephones which includes in its organization magnetizable or polarized means for performing certain functions with relation to the call-recording operation, and means whereby said magnetizable or polarized means may be shunted out from the main phone circuit during talking as well as during the dialing operation.

The present application is a continuation in 30 part of my copending application Serial No. 638,351, filed October 18, 1932.

In the drawings:

Figure 1 is a view in side elevation of a telephone unit showing the improved call-recording mechanism, principally in dotted lines, installed in the base of the telephone;

Fig. 2 is a bottom plan view of the parts of the call-recording mechanism installed in the base of the phone of Fig. 1;

Fig. 3 is an enlarged detail view of the polarized relay cam shunting mechanism;

Fig. 4 is a view taken substantially on the line 4—4, Fig. 2; and Fig. 4a is a view similar to Fig. 4 showing the parts in alternate position; 45 and

Fig. 5 is a wiring diagram of the complete circuit.

Referring in detail to the drawings, the hollow base of the telephone is indicated at 5, the receiver hook at 6, and the transmitter at 7. While I have shown the mechanism installed in the conventional type of upright or standard phone, it will be understood that it could be operatively applied in conjunction with a cradle 50 or French type of phone, or any other type of

phone embodying the usual telephone parts, with minor changes in structure of a simple mechanical nature. The mechanism in the present instance is shown installed in a separate housing 5a which is attached to the base of the phone, but it will be understood that the mechanism could be built into the said base, or the latter could be extended to accommodate the same as desired. 5

The rotatable impulse dial is indicated at 8 and is mounted on a shaft 9. At an intermediate point on this shaft, the conventional impulse dial spring mechanism is mounted, the mechanical parts of such mechanism not being shown in Fig. 1. On the lower end of the shaft 9, a cam plate 10 is secured, said plate having mounted therein 15 a sliding spring-pressed pawl 11. The pawl 11 is adapted to engage a polarized relay shunting cam 12 provided with a series of teeth 12a, a return spring 12c and a limit stop 12d. Cam 12 is also provided with a cam portion 12b adapted 20 to engage a cam-contact point 13 formed on the one leg of a pair of spring contacts 13a and 13b. The contact spring 13a is connected by means of a wire 13c with a spring contact 14a, while the spring contact 13b is connected by means of a 25 wire 13d with a spring contact 14b, the coacting spring contacts 14a and 14b constituting a self-shunting switch for a polarized relay generally indicated at P. Accordingly, the spring contact 14a is connected by means of a wire 14c with the 30 one coil p of the said relay, and the contact spring 14b is connected by means of a wire 14d with the remaining coil p' of said relay.

A counter C of any conventional or desired type is provided, the shaft of which is provided 35 with a ratchet wheel 15, said wheel being actuated in one direction by means of a pawl 16 which extends back to and is pivotally connected to the one arm of a bell crank lever 17, the other arm of said lever having pivotally connected thereto 40 a rod 18 which extends upwardly through the hollow tubular frame of the phone and is pivotally connected to the receiver hook 6, note Fig. 1.

The pawl 16 is maintained under spring pressure by means of the contact spring 14a, which is provided with a boss or analogous member 16a which bears against the one extremity of the spring contact 14a. As will be subsequently disclosed, these contact springs 14a and 14b are 50 automatically closed when the party being called removes the receiver from the phone bearing the number being dialed and the current is reversed in the system.

The polarized relay P is provided with an ad- 55

justable armature 19 which has connected thereto a lever or analogous member 20 extending across and having in its end portion a recess or notch 20a. The end of lever 20 normally rides on the edge of the pawl 16 until the party being called answers, this position being shown in Fig. 4. When the party answers and the current is reversed in the polarized relay P, the lever 20 is moved to the left under the influence of the said relay, as shown in Figs. 4 and 4a, and the notch registers with said pawl 16, whereupon the parts assume the position shown in Fig. 4a, thereby permitting the pawl 16 to move into registration with the ratchet wheel 15 under pressure of the spring contact 14a, simultaneously closing the contacts 14a and 14b.

Also connected to the bell crank lever 17 is a cam rod or analogous member 21 having a cam end 21a adapted to contact a spring-pressed pawl 22, note particularly Fig. 2, the pawl 22 serving to prevent return movement of the cam 12 during the dialing operation, and being moved clear of said cam and permitting it to return to normal position when the receiver is placed on the receiver hook 6, or when the latter is depressed.

The pawl 16 is provided on one side thereof with a cam 16b adapted to engage the lever 20 and move it out of registration with the notch 20a as the said pawl moves back and rotates the wheel 15, so that the parts again assume the position shown in Fig. 4 after the hook has been depressed and the counter actuated.

The wiring diagram for the phone circuit including the automatic counting mechanism is shown in Fig. 5, and this diagram will be utilized in the description of the operation of the mechanism, which follows:

The hook switch, dial impulse springs and dial shunt springs are clearly designated in Fig. 5, these parts being conventional to dial phone circuits. In the positions of the various switch contacts in the diagram in Fig. 5, the receiver is supposed to be on the hook, or the latter is depressed. As will be understood, the dial shunt springs in the usual dial phone serve to shunt out the receiver and transmitter during impulsing, these springs closing when dialing starts and remaining closed until dialing ceases. In the present instance, the circuit is so arranged that these springs also serve to shunt out the polarized relay during dialing.

When the receiver hook 6 moves up, due to removal of the receiver, and the hook switch closes, the circuit is completed through wire L-1, a, contact h, wire a', a2, a3, cam-contact spring wires 13c, 13d, wire a4, a5, through the transmitter, wire a6 and a7, then through the induction coil and through L-2.

Assuming that the party calling now begins to dial. In the usual dial system, the first three numbers or digits are devoted to unchargeable calls, such as trouble calls, a call to the operator, or a call for the long distance operator direct or relayed through the local operator. Thus in dialing such calls, three numbers or letters are used. The relative angular position of the cam 12 with respect to the cam plate 10 may be adjusted so that the cam portion 12b of the cam 12 does not engage the contact member 13 of the spring contact 13b until the dial is given four or more dialing turns. Hence the contact springs 13a and 13b remain closed during dialing of all unchargeable calls, and the circuit remains as above outlined.

Assuming the dial is given four or more turns,

then the cam portion 12b engages the contact member 13 separating the contact springs 13a and 13b, and the circuit is then completed through L-1, a, h, a', relay P, wire a5, transmitter, wire a6, a7, induction coil, and L-2. 5

Assuming now that the party being called answers and removes the receiver of the dialed phone from its hook. The current then reverses at the central office or exchange and the positive line L-2 becomes negative and L-1 becomes positive. This reversal of current acts on the polarized relay, which throws the arm or lever 20 to the left so that the notch 20a registers with the pawl 16, permitting the latter to depress due to the pressure set up by the spring contact 14a and moving the pawl 16 into mesh with the ratchet wheel 15. The circuit is then through L-1, a, h, a', a2, a4, a5, through the transmitter, a6, a7, induction coil, and L-2, the polarized relay being shunted out while the phone conversation ensues.

When the party finishes talking and returns the receiver to the hook or depresses the hook for any reason whatsoever, the pawl 16 is caused to actuate the counter wheel 15 registering the 25 chargeable call.

The dial shunt springs close when dialing starts, as heretofore noted, and remain closed until dialing ceases. It will be noted that when these contact springs close, the polarized relay is 30 shunted out of the circuit, the circuit then being completed through L-1, a, a', a8, dial shunt springs a9, wire a10, a1, induction coil, and L-2.

Should the dial be actuated while the receiver is on the hook or while the latter remains depressed, the pawl 22 remains clear of the cam 12, so that the latter simply returns to its normal position each time the dial is given a turn or partial turn, and no actuation of the counter results. Assuming a chargeable call has been made 40 and the receiver is placed on the hook and the call recorded by the counter, cam 16b on the side of pawl 16 moves lever 20 out of the notch or recess 20a and the said lever and pawl assume the position shown in Fig. 4, while the lever 21 is 45 caused to retract the pawl 22, permitting the cam 12 to return to its normal position ready for a subsequent call or dialing operation.

From the foregoing, it will be seen that I have provided a call-recording apparatus for individual 50 phones which will register only the chargeable calls, or those that are normally listed by the central station as chargeable. While I have shown the counter applied directly to the phone, it will be obvious that it could be installed at a point 55 remote from the phone and operated by means of a suitable electric switch circuit, or analogous means, so that in order to make a record of the calls it would not be necessary to gain access to the room or compartment in which the phone 60 is installed. The parts of the apparatus are simple in construction and may be economically manufactured. Practical experiments have shown that the mechanism is reliable in operation. Certain changes in design and construction 65 may be adopted within the scope of the invention as defined by the appended claims, it being understood that the showing in the drawings is not to be construed as a limitation but simply as a means of explaining the construction and operation of the invention.

The term "receiver hook" in the claims is meant to include any switch-operating member which performs the function of opening and closing the phone circuit, such as the conventional re- 75

ceiver hook in the standard type phone and the depressible member generally used in the French type of phone or those wherein the receiver and transmitter are combined in a single hand unit.

5 I claim:

1. In a telephone system, in combination with an automatic telephone having a rotatable impulse dial, a main phone circuit, a switch for closing and opening said circuit, a counting device, 10 a magnetic means operatively associated with said switch and device, an electrical circuit for said latter means, and means rendered operative through a predetermined number of impulses of said dial for connecting the second-named circuit into said first-named circuit.
  2. In a telephone system, in combination with an automatic telephone having a rotatable impulse dial, a main phone circuit, a switch for closing and opening said circuit, a counting device, 15 a magnetic means operatively associated with said switch and device, an electrical circuit for said latter means, a cam member arranged to be actuated through impulsion of said dial for connecting the second-named circuit into said first-named circuit, and adjustable means operating to render said cam means inoperative until the dial has given a predetermined number of dialing impulses.
  3. In a telephone system of the reverse current 20 type, a phone circuit, a switch for closing and opening said circuit, means for operating said switch, a rotatable impulse dial, a counting device adapted to register calls in sequential order, magnetizable means for automatically operatively connecting said switch-actuating means with said device upon a reversal of current in the phone circuit, and means for automatically shunting said magnetizable means out of the circuit including a cam member arranged to be rotated 25 by said impulse dial.
  4. In a telephone system of the reverse current type, in combination with an automatic telephone having an impulse dial, a phone circuit, a switch for closing and opening the circuit, means for actuating said switch, a counting device adapted to register calls in sequential order, magnetizable means for automatically operatively connecting said switch actuating means with said device upon a reversal of current in the phone circuit, 30 and means operating through rotation of said dial for shunting out said magnetizable means.
  5. In a telephone system of the reverse current type, in combination with an automatic telephone having an impulse dial, a main phone circuit, a switch for closing and opening said circuit, means for operating said switch, a counting device adapted to register calls in sequential order, means for operatively connecting said switch operating means with said device upon a reversal of current 35 in the phone circuit, said switch operating means having a connection with the device such as will cause the latter to be actuated when the circuit is opened.
  6. In combination with an automatic telephone 40 having an impulse dial, a main phone circuit, a counting device adapted to register calls in sequential order, a switch for closing and opening the phone circuit, a receiver hook or analogous member for operating the switch, means for operatively connecting said counting device with said hook, and means rendering said connecting means operative to actuate said device through depression of said hook upon a response to the call number being dialed.
  7. In combination with an automatic telephone 45
- having a rotatable impulse dial, a main phone circuit, a counting device adapted to register calls in sequential order, a switch for closing and opening the phone circuit, a receiver hook or analogous member for operating the switch, means for operatively connecting said hook with said counting device, means normally maintaining said connecting device, means disengaged from said device, and means for moving said connecting means into engaged position with said device upon a response 50 to the call number being dialed.
8. In combination with an automatic telephone having a rotatable impulse dial and a reverse current circuit, a counting device adapted to register calls in sequential order, a switch for closing 55 and opening the phone circuit, a receiver hook or analogous member for operating the switch, means for operatively connecting said receiver hook with said device, means normally maintaining said connecting means disengaged from said device, and magnetizable means adapted to move said connecting means into operative engagement with said counting device upon a response to the call number being dialed.
9. In a telephone system of the reverse current 60 type, in combination with an automatic telephone having an impulse dial, a main phone circuit, a counting device adapted to register calls in sequential order, a switch for closing and opening the circuit, a receiver hook or analogous member for operating the switch, means for mechanically connecting said hook with said device, means normally maintaining said connecting means disengaged from said device, and means automatically operatively connecting said connecting means with said device upon a reversal of 65 current in the main phone circuit.
10. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, means for mechanically connecting said hook with said device, 70 means normally maintaining said connecting means disengaged from said device, and magnetic means operable to move said connecting means into operative engagement with said device upon reversal of current in the phone circuit.
11. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, means connecting said hook with said device, means normally maintaining said connecting means disengaged from said device, and a polarized relay adapted to move said connecting means into operative engagement with said device upon reversal of current in the phone circuit.
12. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, means for actuating said device through depression of said hook, and means rendering said actuating means operable by depression of said hook upon reversal 80 of current in the phone circuit.

13. In a telephone system having a phone circuit of the reverse current type, in combination with an automatic telephone having an impulse dial, a switch for closing and opening the circuit, a receiver hook or analogous member for operating the switch, a counting device adapted to register calls in sequential order, and means for automatically initiating an operative connection between said hook and device upon a reversal of current in the system whereby when the hook is depressed the device will be operated.
14. In a telephone system of the reverse current type, in combination with an automatic telephone having an impulse dial, a phone circuit, a switch for closing and opening the circuit, a counting device adapted to register calls in sequential order, a receiver hook or analogous member for operating the switch, magnetizable means for automatically operatively connecting said receiver hook with said device upon reversal of current in the phone circuit, and means for automatically shunting out said magnetic means upon reversal of the current.
15. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, and a polarized relay for automatically operatively connecting said receiver hook with said device whereby when the hook is depressed the device will be operated, said relay being rendered operative through reversal of current in the phone circuit.
16. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, and a polarized relay for automatically operatively connecting said receiver hook with said device whereby when the hook is depressed the device will be operated, said relay being rendered operative through reversal of current in the phone circuit, and means for automatically shunting out said relay upon reversal of the current.
17. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, magnetizable means for automatically operatively connecting said receiver hook with said device upon reversal of current in the phone circuit, means for automatically shunting out said magnetic means upon reversal of the current, and means for also automatically shunting out said means during the dialing operation.
18. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, a polarized relay for automatically operatively connecting said receiver hook with said device upon reversal of current in the phone circuit, a relay circuit, contact members for connecting said relay circuit with the phone circuit, and means rendered operative

upon a predetermined number of dialing turns of said dial for automatically shunting the relay circuit out of the phone circuit.

19. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, a polarized relay for automatically operatively connecting said receiver hook with said device upon reversal of current in the phone circuit, a relay circuit, spring contact members for connecting the relay circuit with the main phone circuit, and a cam rotatable with the dial for automatically actuating said spring contacts upon a predetermined number of dialing turns of the dial to thereby separate said spring contacts and shunt the relay circuit out of the phone circuit.

20. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, a polarized relay for automatically operatively connecting said receiver hook with said device upon reversal of current in the phone circuit, a relay circuit, contact members for connecting said relay circuit with the phone circuit, means rendered operative upon a predetermined number of dialing turns of said dial for automatically shunting the relay circuit out of the phone circuit, and means for returning said cam to its original position, said means being rendered operative through depression of said receiver hook.

21. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, a polarized relay for automatically operatively connecting said receiver hook with said device upon reversal of current in the phone circuit, a relay circuit, spring contact members for connecting the relay circuit with the phone circuit, a cam for separating said spring contacts upon a predetermined number of dialing turns, and a pawl associated with the dial for actuating said cam through impulsive movements of said dial.

22. In a telephone system of the reverse current type, in combination with an automatic telephone having an impulse dial, a main phone circuit, a counting device adapted to register calls in sequential order, a switch for closing and opening the circuit, a receiver hook or analogous member for operating the switch, magnetizable means for automatically operatively connecting said receiver hook with said device upon reversal of current in the phone circuit, dial shunt springs, said springs being connected into the circuit in a manner such as to shunt the magnetizable means out of the main phone circuit through rotation of said dial.

23. In a telephone system of the reverse current type, in combination with an automatic telephone having an impulse dial, a polarized relay, an electrical circuit for said relay, a switch for closing and opening the circuit, a receiver hook or analogous member for operating the switch, a counting device adapted to register calls

in sequential order, a ratchet wheel for said device, a pawl adapted to engage said ratchet wheel, means connecting said pawl with said receiver hook, and means connecting said polarized relay with said pawl whereby the latter is moved into mesh with said wheel upon reversal of current in the main phone circuit, and means for automatically moving said pawl out of mesh with said wheel.

5 24. In a telephone system of the reverse current type, in combination with an automatic telephone having an impulse dial, a polarized relay, an electrical circlit for said relay, a switch for closing and opening the circuit, a receiver hook or analogous member for operating the switch, a counting device adapted to register calls in sequential order, a ratchet wheel for said device, a pawl adapted to engage said ratchet wheel,

means connecting said pawl with said receiver hook, means connecting said polarized relay with said pawl whereby the latter is moved into mesh with said wheel upon reversal of current in the main phone circuit, and means for automatically 5 moving said pawl out of mesh with said wheel.

25. In combination with an automatic telephone having an impulse dial, a switch for closing and opening the circuit, a receiver hook or analogous member for operating the switch, 10 means for registering calls in sequential order, and means for automatically operatively mechanically connecting said hook with said recording means upon a response to the call number being dialed.

15 JACOB E. LASKIN.
